UNITED STATES PATENT OFFICE.

PETER M. ANDERSON, OF WOODVILLE, AND ALFRED L. HALVERSON, OF SPRING VALLEY, WISCONSIN.

AUTOMATIC STOP FOR CHURNS.

Application filed November 27, 1925. Serial No. 71,828.

Our present invention has for its object to provide a simple and highly efficient automatic stop for churning, and to this end it consists of the novel devices and combinations of devices hereinafter described and defined in the claims.

As is well known, churning is given a predetermined number of revolutions to produce the required churning action, and to 10 notify the attendant when the number of revolutions has been completed, an audible alarm such as a bell is usually provided and arranged to be actuated by a movable part of the churn. With such an alarm the attendant must always keep close to the churn so that he can stop the same when the alarm is sounded. By the use of our invention, an attendant having started a churn may go 15 away and do other work and at the completion of the churning action, the churn will be automatically stopped by the disconnection of the driving mechanism thereof by operating the clutch or by throwing a switch when the churn is operated by a motor.

20 In the accompanying drawings, which illustrate the invention, like characters indicate like parts throughout the several views.

Referring to the drawings:

Fig. 1 is a fragmentary perspective view 25 of a combined churn and butter worker equipped with the invention;

Fig. 2 is a fragmentary view principally in section of the invention and a part of the combined churn and butter worker;

30 Fig. 3 is a detail view with some parts sectioned on the line 3—3 of Fig. 2;

Fig. 4 is a back view of the ratchet wheel;

Fig. 5 is a perspective view of the trip finger and attaching member; and

40 Fig. 6 is a plan view of the same.

Of the parts of the combined churn and butter worker to which the invention is applied, it is important to note the frame 7, barrel 8 and driving mechanism for the 45 churn barrel, and its rolls indicated as an entirety by the numeral 9, with the exception of the driven pulley 10 over which runs a driving belt, not shown, clutch 11 for connecting said pulley to the driving mechanism, and the clutch shift lever 12. Said invention in its preferred form, provides means carried by the barrel 8 for automatically releasing the clutch 11 to stop said churn after it has made a predetermined

number of revolutions, and which number 55 may be varied at will.

Referring now in detail to the invention, as illustrated, the numeral 13 indicates a weight attached by a cable 14 to the clutch shift lever 12 for moving the clutch 11 axially toward the barrel 8 to disconnect said clutch from the pulley 10 and stop the rotation of said barrel. For supporting the weight 13 in an elevated position from which it can be dropped to release the clutch 11, there is secured in the top of said weight 55 an eyebolt 15 through which extends a horizontal supporting pin 16 carried by a lever 17 pivoted at 18 to a supporting arm 19 on a housing 20. The pin 16 is secured to the lever 17 in a downwardly offset relation in respect to its pivot and extends in the same direction as said lever and parallel thereto.

The lever 17 extends toward the housing 20 and its free end is undercut to afford a 75 cam surface 21 which rests on one end of a horizontal sliding bar 22 and is held thereby in a horizontal position against the action of the weight 13 to swing said lever downward. The cable 14 runs over a guide 80 sheave 23 journaled on the lever 17, and a chain 24, having one of its ends anchored to the outer end of the supporting arm 19 and its other end attached to the eye-bolt 15, is provided to limit the dropping movement 85 of the weight 13. The sliding bar 22 is mounted for endwise sliding movement in seats formed in the sides of the housing 20, and its end portions project outward of said sides. A coiled spring 25 encircling the sliding bar 22 within the housing 20 is compressed between one side of said housing and a pin extending transversely through said bar, and is under strain to draw the sliding bar away from the lever 17 and release the 90 same.

To hold the sliding bar 22 against the tension of the spring 25 the opposite end thereof from the lever 17 bears against the back of a large ratchet wheel 26 secured 100 to a shaft 27 journaled in the sides of the housing 20. Secured to the face of the ratchet wheel 26 is a concentric annular band 28 graduated and numbered at 29 to represent the number of rotations of the barrel 8, and it will be noted that there is one graduation and number for each tooth of the ratchet wheel 26, hence if the barrel 8 is to 105

be given twenty rotations, the twentieth tooth or graduation will be set at the zero mark 20' indicated on the outer face of the housing 20.

Formed in the back of the ratchet wheel 26 directly opposite the zero point of the graduations 29 is a recess 30 into which the adjacent end of the sliding bar 22 will be projected by the spring 25 and the cam surface 21 on the lever 17 to release said lever.

The recess 30 and the adjacent end of the sliding bar 22 have co-operating cam surfaces for camming said bar out of the recess 30 by a forward rotation of the ratchet wheel 26 during the setting action thereof.

A dog 31 pivoted to the housing 20 is arranged to engage the teeth of the ratchet wheel 26 to prevent backward rotation of said wheel. Secured to the face of the ratchet wheel 26 within the band 28 is a finger bar 31 by which said ratchet wheel may be turned.

To impart a step of movement to the ratchet wheel 26 for each rotation of the barrel 8, there is journaled in the housing 20 a rock shaft 32 having a crank 33 to which is pivoted a pawl 34 gravity-held for engagement with the teeth of the ratchet wheel 26. A spring 35 attached to the rock shaft 32 and anchored to the housing 20 holds said rock shaft with the pawl 34 in a retracted position. Secured to the outer end of the rock shaft 32 is a radial arm 36 arranged to be engaged by a trip finger 37 on the barrel 8 which extends parallel to the axis thereof. This trip finger 37 is pivoted to a block 38 secured to the under side of the cylindrical shell of the barrel 8 outward of the adjacent head thereof. A stop shoulder 39 on the block 38 holds the trip finger 37 against pivotal movement and in a position to engage the radial arm 36 and thereby operate the rock shaft 32 and then pass beyond said arm under the rotation of said barrel.

If it is desired to operate the barrel 8 without the automatic stop, the trip finger 37 may be moved into a position in which it will pass by the arm 36 without engaging the same. A radial arm 40 on the rock shaft 32 affords manually operated means by which the pawl 34 may be operated to move the ratchet wheel 26.

The housing 20 is supported on a shelf 41 and is secured thereto by nut-equipped bolts 42 which extend through slots 43 in said shelf to permit said housing to be adjusted toward or from the barrel 8 to properly position the arm 36 in respect to the trip finger 37. The shelf 41 is supported on a standard 44 secured to one of the longitudinal members of the frame 7. This standard 44 comprises telescopically connected members which may be longitudinally adjusted to raise or lower the shelf 41. A horizontal

arm 45 connects the shelf 41 to one of the bearings on the frame 7 and holds said shelf against horizontal movement.

When the lever 17 has been released by the sliding bar 22, at the time it enters the recess 30 at the completion of the number of rotations of the barrel 8, the weight 13 swings the lever 17 downward and slides from the supporting pin 16. The fall of the weight 13, acting on the clutch shift lever 12 through the cable 14, releases the clutch 11 and stops the driving connections to the barrel 8.

What we claim is:

1. The combination with a rotatable member and power means with connections for rotating said member and having a shiftable member for cutting the same out of action, of a wheel adapted to be set in different rotated positions to represent a predetermined number of revolutions of said member, driving means arranged to be operated by said member for imparting steps of movement to said wheel, power means having a connection to said shiftable member for operating the same, a lever releasably holding the power means, and an endwise movable member directly engaging said wheel as a stop for holding said lever against the action of the power means and arranged to be released by said wheel after it has made a predetermined number of revolutions.

2. The combination with a rotatable member and power means with connections for rotating said member and having a shiftable member for cutting the same out of action, of a wheel adapted to be set in different rotated positions to represent a predetermined number of revolutions of said member, driving means arranged to be operated by said member for imparting steps of movement to said wheel, power means having a connection to said shiftable member for operating the same, a lever releasably holding said power means, and a sliding bar extending substantially parallel to the axis of the wheel and engaging the same as a stop and holding the lever against the action of the power means, said wheel having a recess into which said bar will be projected to release the lever after said wheel has made a predetermined number of revolutions.

3. The combination with a rotatable member and power means with connections including a clutch for rotating said member, of a ratchet wheel adapted to be set in different rotated positions to represent a predetermined number of rotations of said member, a rock shaft having a crank-connected pawl co-operating with the ratchet wheel for imparting steps of movement to said wheel, a spring yieldingly holding the rock shaft with the pawl retracted, a crank arm on said rock shaft, a trip finger on said member arranged to engage the crank arm during each rotation of said member to cause

said pawl to impart a step of movement to the ratchet wheel, a weight having a connection to said clutch for releasing the same, a lever releasably holding said weight raised, 5 and a sliding bar engaging the ratchet wheel as a stop and holding the lever against the action of the weight, said ratchet wheel having a recess into which said bar will be pro-

jected to release the lever after said wheel has made a predetermined number of revolutions. 10

In testimony whereof we affix our signatures.

PETER M. ANDERSON.
ALFRED L. HALVERSON.
